UNITED STATES PATENT OFFICE.

HERMAN E. S. CHAYES, OF NEW YORK, N. Y., ASSIGNOR TO CHAYES DENTAL INSTRUMENT CORPORATION, OF NEW YORK, N. Y., A CORPORATION OF DELAWARE.

METHOD OF MAKING DENTAL ATTACHMENTS.

Application filed February 21, 1925. Serial No. 10,782.

This invention relates to a process for making metal anchor members for use in dental bridge work and also to the article produced in carrying out the process.

- 5 A general object of the invention is to provide a method of manufacture of dental anchors by which the articles can be produced in relatively large quantities at a correspondingly low cost.
- 10 The invention includes the use of rolling operations to form an elongated bar so shaped in cross-section that the mere division of the bar into sections produces the finished articles.
- 15 Another feature of the invention resides in the formation on the bar of a flange member adapted to be folded or bent on itself to provide a spring jaw member which will function to exert pressure against the
- 20 wall of a socket in which the completed anchoring member may be seated.

- Another feature of the invention resides in the provision of an anchoring device having a substantially T-shaped section 25 with the head portion folded back on itself along a lateral edge to provide a spring jaw construction.

Other features of the invention will be hereinafter referred to.

- 30 In the drawings, in which a preferred embodiment of the invention has been selected for illustration,

Figure 1 is a view in perspective of a portion of a round bar or wire from which the article is produced.

Figure 2 is a diagrammatic view showing an initial step in a rolling and forming operation which forms part of the invention.

Figure 3 is a sectional view of the stock 40 when it has been subjected to the forming operation shown in Figure 2.

Figure 4 is a view similar to Figure 2 showing another rolling operation to which the blank is subjected.

45 Figure 5 shows the article when it has been subjected to the forming operation shown in Figure 4.

Figure 6 shows the appearance of the article after it has been subjected to a still further forming operation.

50 Figure 7 is a view showing the article when it has been subjected to a bending operation.

Figure 8 is a view similar to Figure 7

showing the article when the fold shown in Figure 7 has been moved to closed position.

Figure 9 is a view similar to Figure 8 showing the article when it has been subjected to a shaving or sizing operation.

Figure 10 is a view similar to Figure 9 showing the article with the fold moved to partially opened position.

Figure 11 is a perspective view showing in disassembled relation a completed anchoring device resulting from the carrying out of the operative steps referred to in the previous figures and also showing a socket member in which the anchoring device is received.

Referring to the drawings for a more detailed description of the invention, in Figure 1 there is shown a round wire or rod 10 which forms the stock or material from which the hereinafter described product is formed. The rod or wire section 10 is 75 formed of metal impervious to acid and other conditions to which dental devices are subjected in actual use.

The first step in the operation of producing dental anchoring devices from the round wire or rod 10 consists in passing the wire section 10 longitudinally between the periphery of an anvil roller 11 and a pair of forming rollers 12 and 13 as is clearly shown in Figure 2 of the drawing. It will be seen 80 that the forming rollers 12 and 13 are placed at an angle to each other and to the anvil roller 11 so that the wire 10 as it is drawn between the peripheries of the rollers is formed into a shape having approximately 85 a T cross-section. The particular formation provided by the first passage of the stock between the rollers shown in Figure 2 of the drawing and it will be seen that a base portion 14 has a lateral extension in both directions and that an upright ridge or stem portion 15 is initially formed in this first 90 operative step.

Referring again to Figure 2 of the drawing a downward pressure is exerted on the rollers 12 and 13 which are placed somewhat to one side, toward the left-hand in Figure 2, so that the flange member 15 which is pressed up between the confronting margins 16 of the rollers 12 and 13 is located to the left of the center of the mass of material under operation. The laterally 100

displaced disposition of the ridge 15 is clearly shown in Figure 3 of the drawing.

The downward pressure which is exerted through the rollers 12 and 13 spreads the material in the stock 10 laterally so that the initial formation of a base flange member is produced with one side of the base portion extending substantially double the distance laterally of the extension produced 10 in the base portion on the other side of the ridge. This unequal distribution of the material in the base member on opposite sides of the ridge 15 is equivalent to saying that the ridge 15 is displaced laterally as has 15 already been pointed out. The purpose of the unequal distribution of the material in the base portion on opposite sides of the ridge member 15 will be hereinafter referred to.

20 Following the initial step of operation which produces the cross-section shown in Figure 3 of the drawing, the partially formed member 10 is again subjected to a rolling operation as is shown in Figure 4 25 of the drawing. In the rolling operation shown in Figure 4, the relative positions of the rollers 11, 12 and 13 is such that the base portion 14 of the stock 10 is greatly reduced in thickness while the ridge portion 15 is 30 extended in height and correspondingly reduced in thickness. The resulting formation produced by operation shown in Figure 4 of the drawing is disclosed in Figure 5.

Following the operation which produces 35 the T-shaped bar shown in Figure 5 of the drawing, the stock is again subjected to a rolling operation similar to those already described which results in a still greater reduction in thickness of the base member 14 40 and an increase in height and corresponding decrease in thickness of the ridge or body portion 15 as is clearly shown in Figure 6 of the drawing. It will be seen from an inspection of Figure 6 that the base member 14 45 has been so greatly reduced in thickness with a corresponding increase in width that the carrying out of a bending or folding operation which results in a formation such as is shown in Figure 7 of the drawing can 50 be accomplished. The bending operation referred to produces a bend or fold in the base portion 14 along the line 17, the distance between the line of fold 17 and the body portion being the same or substantially the same 55 as the distance between the body portion 15 and the edge portion of the base member 14 on the other side of the body portion. The folded portion 18 of the base portion is bent into a position at an angle to the main portion of the base member as is clearly shown 60 in Figure 7.

By following the bending or folding operation which results in the formation shown in Figure 7 of the drawing the formed stock 65 is subjected to a suitable annealing operation

to restore the condition of the metal following the hardening effects produced therein by the working operations referred to.

Following the annealing operation the stock is subjected to an operative step which 70 produces a closing of the fold 18 against the base portion 14 in the manner shown in Figure 8 of the drawing.

Following the closing operation which produces the formation shown in Figure 8, 75 the stock is subjected to a suitable shaving or cutting operation which reduces the device to its final or ultimate size and form. The result of the shaving operation referred to is shown in Figure 9 of the drawing.

Following the sizing operation the formed article is subjected to an opening operation which leaves the fold 18 in a position slightly spaced from the base portion 14 so that these 80 parts tend to separate from each other and thereby exert pressure against the walls of a socket in which they may be placed for use. The elongated, formed and T-shaped bar shown in Figure 10 of the drawing is 85 divided into sections of such length that the individual parts have a sufficient height or length to fit into socket members such as are shown at 19 in Figure 11 of the drawing, the socket members 19 being formed to be seated 90 in the body of pier teeth in a dental bridging operation. In dividing the elongated T-shaped bar shown in Figure 10 into the short sections 20 shown in Figure 11 of the drawing the body portion 15 now becomes a stem 95 member and the parts 14 and 18 in Figure 10 become a flange or head member adapted to be received in the socket member 19 shown also in this figure. The stem portion 15 of the dental anchoring member shown in Figure 11 has a less height or length than that 100 of the head portion made up of the parts 14 and 18. The diminished length of the stem portion 15 is effected by removing a section 105 of the lower portion thereof so that the length of the stem portion which remains is 110 the same or substantially the same as the length of a vertical slot 21 formed in the side of the socket member 19 shown in this figure. The result is that the lower end portion of 115 the head member 14-18 extends below the lower end of the slot 21 into the base portion of the socket 19 to thereby provide an effective anchoring function.

It will be seen that the spring jaw members 14 and 18 which make up the head portion of the anchoring member 20 are 120 united along one of their edges and that they bend along the line of juncture or fold to adapt themselves to the interior of the socket member 19. The outward spring 125 pressure which is exerted by the member 18 produces an adequate frictional engagement with the inner wall of the socket member to prevent accidental removal of the anchoring member 20 from the socket 19. At the same 130

time the resilient nature of the frictional engagement of the parts provides a desirable adjustability and flexible adaptation of the parts to each other under the varying strains

5 to which they are subjected.

The method of manufacture of dental anchoring device which has been described is capable of producing the articles at a low cost of production since the forming operations which are produced by rolling wire or rod stock into elongated shapes of suitable cross-section, are relatively inexpensive to carry out. The subsequent folding, annealing and sizing operations are also capable of being carried out at a relatively low cost. The final transverse cutting operations by which the individual anchoring devices are cut from the T-shaped bar stock and the removal of a section from each 10 resulting stem member can be quickly and inexpensively produced on automatic machines, so that the whole method of operation leads to the production of the described anchoring members in relatively large quantities and at a correspondingly low cost.

25 What is claimed is:—

1. That process for making dental anchoring devices which consists in subjecting an elongated piece of metal to a forming operation to produce therein a T-shaped cross-section in which the flange on one side of the stem has a greater width than the flange on the other side, in folding the flange on itself, and in dividing the formed and folded member thus produced transversely into sections to provide the finished articles.

2. That process for making dental anchoring devices which consist in subjecting an elongated piece of metal to a rolling operation to produce therein a T-shaped cross-section in which the flange on one side of the stem has substantially triple the width of the flange on the other side, in folding

30 the wider flange to bring the edge thereof adjacent the edge of the narrow flange, and 45 in dividing the formed and folded member thus produced transversely into sections.

3. That process for making dental anchoring devices which consists in subjecting an elongated metal rod to a rolling operation 50 to produce therein a T-shaped cross-section in which the flange on one side of the stem has a greater width than the flange on the other side, in folding the flange on itself, in subjecting the formed and folded 55 member to a sizing operation, and in dividing the formed and folded member transversely into sections to provide the finished articles.

4. That process for making dental anchoring devices which consists in subjecting an elongated section of round wire to a series of rolling operations to produce therein a T-shaped cross-section in which the flange on one side of the stem has a greater width 60 than the flange on the other side, in folding the flange to a partly closed position on itself, and in dividing the formed and folded member into sections to provide the finished articles.

5. That process for making dental anchoring devices which consists in subjecting an elongated metal rod to a rolling operation to produce therein a T-shaped cross-section in which the flange on one side of the stem 75 has a greater width than the flange on the other side, in folding the flange to a partly closed position, in annealing the formed rod, in completely closing the folded flange, in subjecting the formed rod to a sizing operation, in partly opening the folded flange, and in dividing the formed and folded member transversely into sections.

70 In testimony whereof I affix my signature.

HERMAN E. S. CHAYES.
